CONTINUOUS BELT-TYPE FLUID
TREATMENT APPARATUSCyrus Katzen and Thomas R. Games,
Washington, D. C.

Application January 14, 1949, Serial No. 70,992

7 Claims. (Cl. 95—94)

1

This invention pertains to fluid treating apparatus, and to improvements therein which are especially adapted, although not limited to, the fluid treatment of photographic films, plates and the like.

It is an object of the present invention to provide an improved fluid treatment apparatus for separate or discrete elements such as photographic negative films or the like, which will be continuous in operation.

A further object of the invention is to provide an apparatus of this kind in which no separate tanks or other fluid containing vessels of conventional types are employed, but in which the fluid receptacles are continuously formed by portions of a traveling belt or the like, which also serves to convey the articles being treated through the apparatus.

Still another object of the invention is to provide a system of the kind indicated in which each portion of the traveling belt serves at times as a conveyor portion, and at other times as a fluid receptacle wall-forming unit, so that the surfaces which are periodically in contact with the various treating fluids are ultimately returned to a state or configuration in which their regular and systematic cleaning may readily be accomplished in a continuous manner.

A further object of the invention is to provide an apparatus of this type in which a traveling belt is caused to follow a path such that its lateral edges are folded upward toward one another to provide treating fluid receiving pockets at spaced points along the travel of the belt, and between successive pockets the belt portions are pressed firmly into contact with one another, so as to exert a wiping or "squeegee" action upon films or the like passing along with the belt, thereby to reduce the degree of contamination of the successive treating fluids by fluid carried over with the belt and film from preceding stages.

An additional object of the invention is to provide for the continual addition of fresh treating fluid to the respective pockets formed by the belt, and for the continual removal of spent or exhausted fluids therefrom, all without interrupting the continuous movement of the belt in its path.

Still another object is to provide a fluid treating apparatus in which the articles, such as photographic films or the like, are held and conveyed between two separate or distinct belts which are arranged to pass into face to face contact with one another during a portion of their travel, the contacting belts together with any material therebetween being arranged to dip into the successive treating fluids.

2

A further object is to provide an apparatus of this type in which articles are conveyed between normally contacting faces of conveyor belts, and in which treating fluids are injected into the space between the belts (largely occupied by the article conveyed thereby) at one point and removed therefrom at another point. The different zones of treatment are defined by spaced squeeze rollers which substantially prevent migration of fluid from one zone into the adjacent zones.

Another object of the invention is to provide an improved and novel method of fluid treatment for articles such as photographic films or the like.

The above and other objects and advantages of the invention will best be understood from the following detailed specification of certain preferred embodiments thereof, taken in connection with the accompanying drawings, in which:

Fig. 1 is a side elevation of one form of machine embodying the invention,

Fig. 2 is an end view of the entrance end of the machine,

Fig. 3 is a plan view of the internal construction of the machine of Fig. 1,

Fig. 3A is a side elevation of Fig. 3,

Fig. 3B is a view, to a larger scale, of a portion of the belt sprocket driving means,

Fig. 4 is a vertical sectional view taken on line 4—4 of Fig. 1,

Fig. 5 is a similar sectional view taken on line 5—5 Fig. 1,

Fig. 6 is a plan view, largely schematic, of a second arrangement similar to that of Fig. 1,

Fig. 7 is a diagrammatic view similar to Fig. 5, and partly in section, of a further modification of the invention,

Figs. 8 and 9 are respectively plan and side elevational views of still another form of the invention,

Fig. 10 is a diagrammatic view in elevation of a further modification,

Fig. 11 is a sectional view taken on line 11—11 of Fig. 10,

Fig. 12 is a sectional view illustrating another modification, and

Fig. 13 is a sectional view (to a larger scale) illustrating a preferred method of applying treating fluids to materials conveyed between separate but adjacent belts.

Figs. 1 and 2 illustrate one form of improved fluid treating apparatus housed in an elongated cabinet 1 provided with an access door 2 hinged at 3 along a lateral wall of the casing and provided with catches 4 to maintain it in light-tight relation to the remainder of the casing. At the

entrance end of the machine (the left end as viewed in Fig. 1), a portion of the end casing wall is deflected inwardly to provide two curved wings 6 defining between them an entrance aperture 5 within which may be inserted films or other articles to be passed through the treatment.

The general treating system of the invention consists in an elongated belt conveyor which is folded lengthwise for a portion only of its travel to provide upstanding pockets or chambers. As best shown in Figs. 3 and 3A of the drawings, which illustrate the apparatus separated from the external housing 1, there are provided side frame supports or angle bars 10, 12 which run the length of the apparatus, and are cross-connected as by transverse braces or angle bar supports 14 and 16. A floor plate or support table 18, relatively narrow in lateral dimension, connects or extends between the transverse braces 14 and 16, and carries at spaced points along its length a plurality of belt roll support brackets or boxes 20, each of which contains a set of two or more (herein four) rollers 22, which may be rubber covered or similarly constructed so as to pinch between them the two halves of a conveyor belt 24 when the latter is doubled upon itself. Each of the rollers 22 is positively driven at the same predetermined speed, as by a sprocket 26 on the lower end of each roller shaft beneath table 18, all of the sprockets being interconnected by a drive chain 28 (see especially Fig. 3) which passes also around guide pulleys 30 and 32, and thence over sprockets on the ends of the shafts of a pair of belt rolls 34, 36 journaled between frame elements 10 and 12 at opposite ends thereof. A suitable motor unit 38 and gear reduction speed controller 40 are provided to drive the roller 36 and also all of the drive sprockets 26 in synchronous relationship.

As best shown in Fig. 3A, the return path of belt 24 passes beneath the table 18 and the side frame 10, 12, and thence upwardly about roller 34, after which it is doubled upon itself and passes in a vertical position between the successive rollers 22. In assembling the apparatus in the first instance, the length of belt 24 is made of such length as to permit the sections of doubled belt between successive roller boxes 20 to be separated somewhat as illustrated in Fig. 3, thus forming between each two successive boxes a pocket or chamber 42 adapted to receive and contain a quantity of a suitable treating fluid. In the case of ordinary photographic films or the like, the successive solutions, reading from left to right in Fig. 3, may be a developer solution, a short-stop solution, a plain water wash, a fixer solution and a second plain water wash. The invention is not, of course, to be limited to these specific solutions; for example, where high speeds are desired, it may be expedient to use other than plain water for the wash baths, for instance a mixture of water and ethyl alcohol or similar volatile drying agent. Also, a terminal portion of the conveyor belt (near the exit end of the machine) may be devoted to the drying of the films or other articles, as by radiant heat or the like.

In passing from one treatment chamber to the next, both the folded belt and any articles, such as a film, pass between the drive rollers 22 which are dimensioned to press tightly against the outer belt surfaces. This operates to squeeze all solution away from the inner belt surfaces, and from the films or the like, back into the pocket from which the film is being withdrawn, and delivers the film into the next pocket with a minimum

quantity of the treating solution adhering thereto. Contamination of the successive baths by carry-over of fluid is thus greatly reduced, as well as is the rate of depletion of the fluid in each of the treatment pockets.

In order to provide for the replenishment of the fluids in the various pockets, or for the injection of fresh solutions thereinto, we have illustrated a series of storage tanks 44 shown by way of example as located above the path of travel of the belt, although it will be apparent that such storage tanks may equally well be located beneath or to either side of the belt if suitable pumps or the like are provided to force the fluids from said tanks into the respective pockets. The storage tanks and their contents may be maintained at the desired temperature by supplying heat or refrigeration in accordance with well known procedures. In the gravity feed system shown by way of example in the drawings, each of the tanks 44 is provided with an outlet conduit 46 which may be controlled by a valve or the like to regulate the flow of solution therefrom into the corresponding treatment pocket formed by the belt. In cases where pumps are used to convey fluids from the storage tanks, the flow may be governed by controlling the rate of delivery of the pumps.

The continuous removal of solution from each pocket may be carried out in various ways, for example by simple overflow from a notch or the like formed at spaced points along one or both edges of the belt, the notches or hole forming outlet wiers along the upper edge of the folded belt. Equally well, as will be described in connection with Fig. 7, the outlet may be provided by a series of holes formed through the material of belt 24 along its center line, which holes will, therefore, be located at the bottoms of the respective pockets, the size of the holes being chosen to provide a proper rate of removal of solution from the bottom of each pocket. The liquids so removed may be collected in individual sumps for return to the storage tank 44, or if desired may be conveyed to a suitable drain. As shown in the drawings, however, such removal of solution may also be accomplished by a simple siphon arrangement 48 dipping into each pocket 42 and draining a controlled amount of its contents continuously to either a common drain sump, or (where water supply is critical) to individual drains, some of which may discharge to water purification or the like apparatus to permit continuous recirculation of the water, which might otherwise be used in large quantities. Solutions other than water, of course, may also be recirculated and/or purified in the same manner, where conditions warrant.

We have found that the belt 24 may be formed of various materials; fairly thin rubber or flexible plastics such as vinyl plastics may be used, or cloth which has been subjected to a waterproofing treatment. The important characteristics are sufficient pliability or flexibility to enable the material to be folded along its length within a reasonable distance, and a resistance to cracking or perforation in the region of the fold.

To aid in the formation of the pockets 42 by the belt, it is desirable to secure to the bed plate 18 a forming member 50 best shown in Fig. 5 as an approximately V-shaped section of sheet metal or the like, the upper edges 52 of which are rolled over to receive the horizontal edges of belt 24 therein and to guide the same laterally and thereby to produce the open pocket 42.

Various means may be employed to assist in the drying of films or similar articles as they are removed from the last treatment stage of the apparatus. Such means may comprise a blower, indicated schematically at 54 in Fig. 3, with or without one or more infra-red lamps 56 or equivalent drying mechanism. Inasmuch as the films or other articles leaving the final treatment stage are drawn between the pressure drive rollers 22 defining the end of that stage, there will be no excess of moisture adhering thereto as they pass out upon the flattened portion of the conveyor belt 24 at the exit end of the apparatus. For purposes of removing traces of chemical contamination from the belt 24, brushes, scrubbers or the like may readily be positioned to operate on the under-surface of said belt as it returns along the bottom of the machine from roller 36 to roller 34.

In cases where the apparatus is to be installed between a darkroom and some other space, the casing 1 of Figs. 1 to 3 may be omitted and the apparatus installed so as to pass through a suitably light-trapped aperture in the darkroom wall, with the entrance slot 5 on the darkroom side. In such cases the apparatus is to be located so that the initial portion of the treating section will also lie within the darkroom, whereby films or the like passing into the other space will be in a condition in which they will not be injured by light striking the apparatus. Films or other articles which have been conveyed through the entire treating process will emerge from between the doubled belt halves at the right end of the machine in Fig. 1, and from that point may be removed by hand, allowed to accumulate as in a drawer 7 or other receiving compartment, or handled in any other desired manner.

While we have so far described the apparatus in connection with discrete films or other separate articles, it is clear that the same apparatus may be used for treating strips of material such as roll films or the like. In such cases, one end of the strip of film or the like is merely inserted between the doubled-over portions of the belt at the entrance end, and the remainder of the strip suitably supported (as by hand) until the machine has drawn the entire length into the treating area of the belt.

For purposes of conserving space, or making a more efficient utilization of available floor area, it is feasible to arrange our improved type of fluid treating apparatus in other than a straight line as in Fig. 1. Fig. 6 of the drawings schematically illustrates an embodiment in which the conveyor system has been folded back upon itself into a square U formation. In this form of the invention, the turning of the conveyor belt in its folded condition may readily be accomplished by arranging certain of the sets of rollers 20 at right angles to one another. In this embodiment the return half of belt 24 beneath the support table 60 may be defined by a pair of rollers 62 lying at 45° angles to the general direction of the legs of the U. The arrangement of drive sprockets, motors and fluid supply and removal systems have been omitted from Fig. 6 since these may be of a type identical with those disclosed in connection with Figs. 1 and 2 of the drawing. The essence of our present invention lies in the elimination of separate stationary fluid treating tanks, and of the mechanism necessary to direct a conveyor through such tanks, by so arranging the belt or conveyor as to cause it to form, itself, a series of fluid-containing pockets, chambers or

the like through which articles may be moved in succession by the conveying action of the same belt. It will be readily understood that the device when in operation is loaded by the insertion of the article to be treated within the nip of the belt as it enters the first set of vertical driving rollers, after which the transmission of the article through the succession of treating baths is completely automatic, and the treated article is automatically discharged into a suitable container from the belt as it emerges from the nip of the last set of vertical drive rollers. In order to accomplish a change in the length of time in which an article remains in the bath, the speed of the conveyor belt may be caused to vary by any conventional speed controlling means (such as that indicated diagrammatically in Fig. 3 by numeral 40). We have found that a conveyor belt speed of the order of 3" per minute is satisfactory for the treatment of such articles as a dental X-ray film 64 (indicated in dash lines at the left of Fig. 3A) but the speeds and the dimensions of the machine may be widely varied without departing from the basic concept of our invention.

Fig. 7 of the drawings is a vertical sectional view of a modified form of the apparatus described above, in which a doubled portion of the conveyor belt is designated by numeral 65. 30 In this modification, the amount of slack in the belt between successive sets of driving rollers is made as small as possible, so that the doubled halves of the belt, and the mouth between the adjacent belt edges, are normally closed or in 35 face-to-face relation. Between the successive sets of drive rollers, however, the side walls of the folded belt are ballooned outwardly by the pressure resulting from the introduction of the treating fluid. The lower edge of the doubled 40 belt (at the fold line) is provided with perforations as indicated at 66, which communicate with a hole formed through a belt-supporting Y-shaped member 68. Liquid passing through orifice 66 thus reaches a sump 70 and is returned 45 by a pump 72 driven by motor 74, and via a conduit 76, to a point on the upper edge of the folded belt. Conduit 76 there terminates in an injection nozzle 78 of sufficiently small size to lie between the adjacent belt edges and be held 50 in fluid-tight relation thereto because of the tension in the belt material, which tends to hold the edges in intimate contact except at the point where nozzle 78 passes between them. It will be understood that fluid purification means may be 55 provided between the outlet 66 and the inlet nozzle 78, as suggested above. Also, the use of an inserted nozzle 78 for injecting fluids between the belt portions is not limited to systems which utilize recirculation; where the spent fluid is of no 60 value, it may be conveyed from orifice 66 directly to a drain pipe.

The forms of the apparatus described above deal entirely with the use of a doubled belt whose fold line is vertically beneath those belt edges 65 which define the opposite end of the treating pocket or chamber. The principles of the invention, however, may also be applied in apparatus in which the treating pockets or chambers are defined by horizontally arranged belt portions. In Figs. 8 and 9, the doubled section 80 of the belt 82 is arranged for travel in a horizontal plane defined by the successive drive roll assemblies 84. As best shown in Fig. 9, those sections of the doubled belt lying between successive drive roll assemblies may be deflected downwardly

beneath guide rolls 86 and into a series of treating fluid receptacles 88, so that a film or like article introduced between the sides of the doubled portion as indicated by arrow 90 will be carried through the succession of treating baths and discharged at the opposite end of the machine.

Another form of the invention utilizing horizontally arranged belts is illustrated in Figs. 10 and 11 of the drawings, the former showing an upper belt 92 supported on rollers 94 arranged to cause the lower pass of the belt to lie in a horizontal plane in close proximity to the upper pass of a lower belt 95 guided upon rollers 98. Driving power for the "sandwich" is furnished by sets of drive rollers 100 similar to drive rollers 15 22 of Fig. 3; between successive sets of drive rollers there may be arranged open-top treating fluid receptacles 102 into which the superimposed belts may be deflected as by guide rollers 104, so that a film or like article introduced as indicated by arrow 106 will be carried between the belts and through the successive treating baths. A drying lamp 108 or equivalent drying apparatus as described in connection with the previous embodiments may be provided adjacent the exit end of the apparatus. In this form of apparatus, treating fluid reaches the article held between the belts by transmission between the belts through the normal interstices which will be formed at the belt edges by provision of the proper amount of slack between the progressive sets of drive rollers 100. This is preferred over the utilization of porous belts, for the reason that while impervious belts will be "squeegeed" satisfactorily by the successive sets of drive rollers, a porous belt material would necessarily carry over solutions from one receptacle to the next with a consequent increase in fluid contamination. It has been mentioned above that the maintenance of belt edges in sealing contact with one another may be achieved by proper control of the slack between successive sets of drive rollers. Where required, auxiliary means such as the channel-shaped clips 106 of Fig. 12 may be provided. These clips will extend along such portions of the belt edges as required to be held in sealing relation to one another, and will be fixed with respect to the apparatus frame so that the belt portions will slide between the opposed lateral surfaces of the clips. Numerals 50 108 and 110 designate separate but adjacent belt sections in this figure, and between them there is illustrated a photographic film 64 or like article undergoing treatment.

An alternative method of introducing treating fluid to the spaced pockets or chambers formed between congruent belt portions (such as those of Fig. 10), is illustrated in Fig. 13. Instead of deflecting the superimposed belts downward into treating fluid receptacles, the belt edges are again held in close contact by clips 112 similar to those of Fig. 12, these being suitably apertured at each treating station to receive a fluid inlet nozzle 114 which passes between the belt edges and conveys the fluid into the pocket 116, for example from a pump 118 or other suitable supply. Fluid so introduced fills the pocket or chamber 116 and is removed therefrom at the opposite edge of the belts by an exit tube 120. The general flow of treating fluid in accordance with this method is, therefore, in a direction cross-wise of the belts, which is to say at substantially a right angle to the direction of movement of the article 64 being treated. This method of treatment presents great advantages in compact-

ness of the equipment, ease of control of the amount of treating fluid applied to each article and entails minimum waste of such fluid.

While we have disclosed certain preferred embodiments of our improved method and apparatus in accordance with the principles of the invention, we wish it to be understood that the details disclosed herein are largely exemplary, and may be widely varied without departing from the spirit of our invention as defined in the appended claims.

We claim:

1. Fluid treating apparatus comprising a conveyor belt of flexible material arranged for travel between substantially horizontal rollers, and means for deforming said belt into a succession of separate, upwardly opening pockets closed at their bottom edges and adapted to contain treating fluids.

2. Fluid treating apparatus comprising a framework, spaced horizontal belt rollers journaled in said framework, an endless conveyor belt of flexible material passing around said rollers, vertical rolls supported by said framework between said rollers and arranged to guide a portion of said belt into folded condition, means for forcing opposite sides of a folded portion of said belt into contact with one another along horizontally spaced vertical lines to form spaced pockets, and means for introducing treating fluids into said pockets.

3. Fluid treating apparatus comprising a conveyor belt, means for driving said belt along a predetermined path, means for deflecting a portion of said belt into an upwardly-opening doubled condition, means for forcing into intimate contact with one another elements of the deflected portion which are spaced from one another in the direction of travel of said belt to provide a treating chamber, means for returning said belt to flattened condition at a later point in said path, and means for introducing treating fluid into said chamber for contact with articles conveyed between the doubled portion of the belt.

4. Fluid treating apparatus for developing, fixing and washing photographic plates or films or the like, comprising a light-tight housing, means defining an entrance aperture at one end of said housing, a belt conveyor in said housing having at least a portion of its length arranged in doubled condition to define separate upwardly opening pockets or chambers, means for guiding articles to be treated through said aperture and into the grip of the doubled belt, means for introducing treating fluids into said pockets and means for driving said conveyor.

5. Fluid treating apparatus of the character described comprising a conveyor belt for relatively wide, flat, flexible material, means for driving said belt past a series of treating stations, means for deflecting said belt into laterally doubled-over condition in advance of the first treating station, means adjacent each station for forcing the doubled-over belt portions into contact with one another at spaced points, means for maintaining the doubled-over belt portions spaced from each other intermediate said points to define spaced treating chambers, and means for driving said belt to convey articles through said treating chambers.

6. Fluid treating apparatus comprising a belt conveyor having liquid-impervious belt portions arranged for travel in close face-to-face relation with one another, means for applying a succession of treating fluids to the space defined between

said belt portions at spaced stations in their travel, and means for forcing said portions toward and into sealing contact with one another at points intermediate said spaced stations.

7. Fluid treating apparatus comprising a belt conveyor having a doubled portion arranged for travel with its doubled halves in face-to-face relation with one another, means for applying a succession of treating fluids to the space defined between said halves at spaced stations in their travel, and means for forcing said halves toward and into contact with one another at points intermediate said spaced stations to define separate pockets to receive said fluids.
